UNITED STATES PATENT OFFICE.

CHARLES HUMMEL, OF ST. LOUIS, MISSOURI.

ROLLING WINDOW-BLIND.

SPECIFICATION forming part of Letters Patent No. 531,944, dated January 1, 1895.

Application filed April 4, 1894. Serial No. 506,245. (No model.)

To all whom it may concern:

Be it known that I, CHARLES HUMMEL, of the city of St. Louis and State of Missouri, have invented certain new and useful Improvements in Rolling Window-Blinds, of which the following is a full, clear, and exact description, reference being had to the accompanying drawings, forming a part hereof.

The object of this invention is to provide improved means for excluding light from a room, and permitting the entrance of air thereto.

My invention consists in the novel construction, combination and arrangement of parts hereinafter specified and claimed.

Referring to the drawings: Figure 1 is an outside elevation of a window, illustrating the application of my device. Fig. 2 is a sectional elevation on the line 2-2 of Fig. 1. Fig. 3 is a horizontal section on the line 3-3 of Fig. 1. Fig. 4 is an enlarged horizontal section on the line 4-4 of Fig. 2. Fig. 5 is a vertical section on the line 5-5 of Fig. 6. Fig. 6 is a face view of Fig. 5. Fig. 7 is a vertical section of the preferred rollable curtain. Fig. 8 is an inside view of the connecting straps therefor.

In the construction of the device as shown, the numeral 10 designates a window-sill, and 11, 11 the jambs of the frame, and 12 the header thereof. Formed in the header 12 is a slot 13, and located transversely of, and above the said header, in a cavity 14 formed therefor, is a shaft, or drum, 15. Fixed to, and mounted upon, the shaft 15 is a curtain, or blind, 16, which said blind depends through the slot 13 to a point in contact with the sill 10 outside of the window.

The blind 16 comprises a plurality of slats 17, fixed at their opposite ends and centers to suitable metal straps 18, or strap sections 27 the said slats having transverse oblique apertures 19 therein, which said apertures have their outer ends in a lower plane than the inner ends thereof. The slats 17 are each provided with shoulders 20, adapted to overlap the exterior face of the slat next below the same, and the corners of the adjacent edges of said slats on the interior thereof, are cut away.

Fixed to the lower end of the blind 16 is a bar 21, which said bar is provided with trans-

verse slots 22, adapted for manual engagement, whereby the said blind may be drawn downwardly.

Mounted upon the opposite end portions 55 of the drum 15 are drums 22^a, 22^b of greater diameter than the drum 15, and fixed to, and wound upon, the said drums 22^a, are cables, or cords, 23, 23, which said cords depend through pockets 24, 24 provided therefor in the window frame to points of attachment to screw-hooks 25, 25, located in the lower portion of said pockets.

A door 26 is formed in the window frame, adjacent to each of the screw-hooks 25, and 65 providing access to the pockets 24, 24.

In the preferred roller curtain, the details of which are shown in Figs. 7 and 8, the slats 17 are individually mounted upon strap-sections 27, by means of screws 28, the said screws 70 being seated in the said strap-sections and passed through slots 29 in the next adjacent strap-section, the end portions of the strap-sections overlapping each other, as shown in Figs. 7 and 8, thus providing a sliding connection between the said sections and permitting the vertical movement of the slats independently of, and relative to, each other. A plurality of the sections 27 are joined to form a strap, the length of the completed curtain, or blind, and three of these straps are employed passed through vertical apertures in the end portions, and centers, of the slats 17.

This device is mounted upon a drum, and manipulated in the same manner, as is described in connection with the device shown in Fig. 1.

The operation of this device is as follows: When it is desired to elevate the blind, the same being in the position shown in Figs. 1 90 and 2, the door 26 is opened, the cord 23 adjacent thereto, released from the screw-hook 25 and pulled downwardly, thus unwinding the said cord from the drum 22, rotating said drum, rotating the drum 15, and winding the 95 blind upon said drum 15. The cord is then reattached to the screw-hook 25, and retains the curtain, or blind, in an elevated position, so long as desired.

When it is desired to employ the blind 16 100 as a shade, the cord 23 is released from the screw-hook 25, and the blind drawn down-

wardly by the application of manual force to the bar 21.

It is obvious that in the practical use of this device, the light may be entirely excluded, and the air as well, by approximating the slats, or any number of light and air admitting apertures may be provided by separating said slats, longitudinally of the straps.

It will be observed that the shoulders 20, 10 on the slats, overlapping the contiguous edge of a slat next below the same, will prevent the introduction of the direct rays of the sun therethrough.

What I claim is—

In a device of the class described, the com-

bination of a curtain comprising a plurality of slats provided with a plurality of vertical apertures therein, and strap sections provided with slots in one end and mounted in said vertical apertures by means of screws or pins, 20 thus allowing the blind-slats to be separated a slight distance from each other, or to be positioned in contact with one another, thereby making a practically closed flexible blind.

In testimony whereof I affix my signature in presence of two witnesses.

CHARLES HUMMEL.
